(57) **CLAIM**

An ornamental design for a rock planter, as shown and described.

DESCRIPTION

FIG. 1 is a top isometric view of the rock planter showing my new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken line in the drawings is included to show a line that forms no part of the claimed design.

1 Claim, 4 Drawing Sheets# US D761,156 S
